UNITED STATES PATENT OFFICE.

WASHINGTON I. TUTTLE, OF BALTIMORE, MARYLAND, ASSIGNOR TO THE AMERICAN TOBACCO COMPANY, OF NEW YORK, N. Y., A CORPORATION OF NEW JERSEY.

COLLAPSIBLE BOX.

No. 888,943.

Specification of Letters Patent.

Patented May 26, 1908.

Application filed July 24, 1907. Serial No. 385,249.

To all whom it may concern:

Be it known that I, WASHINGTON I. TUTTLE, a citizen of the United States, residing at Baltimore, in the State of Maryland, have invented new and useful Improvements in Collapsible Boxes, of which the following is a specification.

The present invention relates to collapsible boxes of that type in which packed goods or commodities are sold, and which, after the original contents have been consumed, may be readily utilized for other purposes, particularly as lunch kits or pails.

The present invention is intended particularly as an original package in which tobacco may be packed and sold, it being so designed as that it will form a compact, secure receptacle for tobacco when it is in collapsed condition, and one which may be readily packed and shipped and handled by the retailer, but which, after the purchaser has consumed the contents, is convertible into a convenient extensible lunch bucket.

Broadly considered, this type of box is not new, and my present improvements have to do with certain structural details whereby a more compact and rigid arrangement of collapsible sections is secured, and a box is provided which is better calculated to meet the needs of the original use for which it is designed, namely, a tobacco package, as well as the needs of a lunch kit, to which use it is put after its contents have been used.

Briefly stated the invention comprises a plurality of telescoping sections which, in the present instance, are shown as interiorly telescoping sections, which, in collapsed condition, provide a box or receptacle having a substantially unbroken interior surface, and which, in extended position, gives receptacle of considerable capacity. The box is provided with a hollow top which is designed to be reversed so that when the box is in collapsed position, the cover has an ordinary smooth top, while in the reversed condition of the cover it has a filling funnel and closing cap through which the hollow top may be filled with coffee or other liquid during the use of the box as a lunch kit.

In order that the invention may be understood by those skilled in the art, to whom this disclosure is addressed, I have shown in the accompanying drawings one embodiment of my invention, and in such drawings:

Figure 1 is a view in perspective of the box and the cover in collapsed condition, the cover being separated somewhat for clearness of illustration. Fig. 2 is a longitudinal, central, sectional view of the box in collapsed condition. Fig. 3 is a longitudinal, central, sectional view of the box in extended position with the cover reversed from the position shown in Fig. 2. Fig. 4 is a transverse sectional view of the box collapsed. Fig. 5 is a detail view of a portion of the end of the box to show the provision for the lap seams of the box. Fig. 6 is a detail view of the stop and bail ear with which the box is provided. Fig. 7 is a detail sectional view to show the relation of the lap seams of the box sections to one another. Fig. 8 is a transverse section of the meeting ribs between two of the sections taken on the line of the lap seam. Fig. 9 is a detail view of a slightly modified form of cover.

Referring to the drawings by numerals, like numbers indicating like parts in the several views, 2 indicates the outer section of the box, which, as shown, is open at top and bottom and is provided at its bottom with an in-turned rib 3 and at its top with an out-turned rib 4, as is clearly shown in Fig. 2, these ribs serving to stiffen the section, and in the case of the lower rib 3 forming the means which engages the adjacent telescoping section, and these ribs may, if desired, be stiffened by wire centers in the usual manner. Within the said outer section, and telescoping in contact with the inner wall thereof, is the next section 5 which is open at the top and bottom and is provided with the out-turned top rib 6 and the in-turned bottom rib 7, as shown, the out-turned rib on this section 5 engaging the in-turned rib 3 at the bottom of the section, as shown in Fig. 3.

The inner section 8 is shown in the present instance as being the bottom section of the series of three sections shown in the present case, although it is obvious that any number of sections may be employed, and this said inner section 8 has at its top the out-turned rib 9, designed to engage the in-turned rib 7 on the intermediate section when the box is extended (see Fig. 3). This inner section 8 has secured to its lower edge the bottom 10, which is secured thereto by a suitable crimp 11 engaging the lower edge of the section 8 in the manner shown in Fig. 2.

In order that the sheet metal of which these sections are formed may be cheaply and conveniently secured together at their meeting ends by means of the ordinary lap seam 12, as shown in Fig. 7, and yet not interfere with the telescoping movement of the sections or each other, I preferably provide the out-turned top ribs of the several sections with cutaway portions or notches 13 (see Figs. 5 and 8), which notches give clearance for the travel of the lap seams and yet permit a close relation between the out-turned top ribs and the abutting surfaces of the adjacent sections.

A further and important feature of this construction is that the outstanding vertical seams 12, in conjunction with the rib-notches 13, serve to keep in alinement and guide the sections in their telescoping movements, thereby reducing the chances of displacement and jamming of the sections.

In order that the several sections may not be displaced by being telescoped upwardly out of their nested relation with each other, I provide a stop 14 against which the upper edges of the sections strike when the box is in collapsed position and by means of which they are prevented from being disengaged, it being obvious that the engaging ribs of the several sections will prevent the sections being disengaged in their downward movements and extended to the extended position shown in Fig. 3, and by this arrangement of ribs, which prevent the sections being disengaged when extended, and the stops 14 which prevent the sections being disengaged when collapsed, a sectional box is provided in which all danger of parts becoming disarranged or disconnected and perhaps lost, is avoided. These stops 14 are preferably in the form shown and comprise the forked angularly-placed member and the vertical attaching member, the forking of the member 14 being desirable in order that the vertical attaching member may be readily bulged at 15 to engage or provide for the bulge of the lap seam 12. The said stop 14 is preferably and conveniently secured by passing the securing tongue 16 of the bail carrying ears directly through the material of the box and the stop member 14 and clinching them down in the manner shown in Figs. 1, 5 and 6.

The cover 17 is made as shown in the form of a shallow receptacle, being preferably made up in two parts joined by a lap seam which is extended to provide a cover or lid rim 18 which rests on the top of the outer section 2 when the cover is in position.

The contour of the cover at its periphery is the same on both sides, being curved as shown, in order that it may not only be easily entered and held by frictional engagement with the box section 2, but when the box is in collapsed position the said cover 17 will rest upon the interiorly collapsed sections of

the box, as clearly shown in Fig. 4, and will effectually seal or close the tops of these sections so that an absolutely tight closure is provided for all of the sections of the box, and this I consider to be of considerable value as it prevents both the escape of the contents of the package by creeping over the edges of the tops of the inner sections and working down between the walls of the sections, but it also prevents the ingress of dust or dirt which might work in between the sections and over their tops into the package.

Preferably, in order to give rigidity to the top 17, I stamp or rib the same at the point 19, this stamping of the metal giving a rigidity to the otherwise flexible sheet, which aids materially in resisting buckling strains. The other side of the top 17 is provided with the funnel or neck 20 which receives the slip cover 21, and it will be observed that in collapsed condition as shown in Figs. 2 and 4, this downwardly projecting neck 20 with its cover 21 bears upon or is in close relation to the bottom of the box so that it serves to brace the bottom 10 against inward strain.

In the form of the top shown in Fig. 9, the slip cover 22 is extended so that when inserted its lower edge bears against and braces the opposite side of the top 23 as shown, and this construction adds rigidity to the top, enabling the same to be made of relatively thin stock and yet avoid the danger of battering or buckling the top out of shape during usage.

From the foregoing it will be seen that the construction of box which I have invented and herein disclosed, is such that a relatively inexpensive stock may be used in making it up, no expensive seams or unions between the parts to permit the telescoping arrangement are necessary, and yet a box is provided which will stand the ordinary handling to which it is subjected, both in the original packing and shipping, and in using it as a lunch kit after its original contents have been consumed, without danger of becoming broken or distorted so as to render it unfit for use.

It is obvious that the details of construction may be varied without and yet be within the purview of my invention, and I do not, therefore, limit myself to the details disclosed except in so far as I am limited by the prior art to which the invention belongs.

Having fully disclosed my invention, I claim:

1. A collapsible box comprising a series of upwardly and interiorly telescoping sections, the outer section extending above the inner sections when the box is collapsed, and a cover fitted interiorly to and supported solely by the outer section, said cover having a downwardly curved and inclined wall bearing against and sealing the upper edges of the several sections when said cover is inverted.

2. In a collapsible box and in combination, a series of independent upwardly and inferiorly telescoping sections, means for locking said sections against separation in extended position; and a stop carried by the outer section against which the upper edges of the inner sections abut to prevent separation of the sections when collapsed. 5
3. In a collapsible box and in combination, a series of telescoping sections, means for preventing separation of said sections in extended position, a stop carried by the upper section to prevent separation of said sections in collapsed position, and a bail-ear on said upper section having securing lugs passing therethrough and through said stop to secure the stop and bail-ear in place. 10
4. In a collapsible box and in combination, a series of telescoping sections, means for preventing separation of said sections in extended position, a stop carried by the upper section to prevent separation of said sections in collapsed position, a bail-ear on said upper section, and a common fastening to secure said ear and stop in place. 15
5. In a collapsible box and in combination, a series of telescoping sections, reversely turned interlocking top and bottom ribs on said sections, said top ribs having cut-away portions, and vertical guide ribs extending lengthwise of said sections to engage said cut- 20
- away rib portions and hold the sections in vertical alinement and guide their relative movements. 25
6. In a collapsible box and in combination, a series of telescoping sections, outstanding vertical seams on said sections, and reversely turned interlocking top and bottom ribs on said sections, said top ribs having cut away portions to receive the vertical seams, whereby the sections are alined vertically and guided in their telescoping movements. 30
7. In combination with a box, a hollow reversible cover, a neck extending outwardly from one wall of said cover, a closure for said neck which when inverted bears against and braces the box bottom against buckling, and a central stiffening rib on the lower wall of said cover. 35
8. In combination with a box, a hollow reversible cover, a neck on one side of said cover, and a slip closure for said neck having an extended body portion which extends through the hollow cover and bears against and braces the lower side thereof. 40
- In testimony whereof I have hereunto set my hand in presence of two subscribing witnesses. 45
